Fig. 1

Fig. 2

Fig. 6

Fig. 5

FIG. 1 is a front view in elevation of a tool change arm for transferring tools between a tool storage magazine and a tool operator illustrating my new design in the open condition;

FIG. 2 is a left side view in elevation of the tool change arm for transferring tools between a tool storage magazine and a tool operator shown in FIG. 1;

FIG. 3 is a right side view in elevation of the tool change arm for transferring tools between a tool storage magazine and a tool operator shown in FIG. 1;

FIG. 4 is a plan view of the article transfer arm shown in FIG. 1;

FIG. 5 is a perspective view of the tool change arm for transferring tools between a tool storage magazine and a tool operator shown in FIG. 1 with the arm being illustrated in the open condition; and

FIG. 6 is a perspective view of the tool change arm for transferring tools between a tool storage magazine and a tool operator shown in FIG. 5 with the arm being shown in the closed condition for grasping the articles to be transferred.

I claim:

The ornamental design for a tool change arm for transferring tools between a tool storage magazine and a tool operator, as shown and described.
